UNITED STATES PATENT OFFICE.

WILLIAM RILEY, OF YOUNGSTOWN, OHIO.

WATER-GAGE.

1,128,516.

Specification of Letters Patent. Patented Feb. 16, 1915.

Application filed August 19, 1914. Serial No. 857,587.

To all whom it may concern:

Be it known that I, WILLIAM RILEY, a citizen of the United States, residing at Youngstown, in the county of Mahoning and State of Ohio, have invented certain new and useful Improvements in Water-Gages, of which the following is a specification, reference being had to the accompanying drawings.

19 This invention relates to gages, and particularly to water gages adapted for use in connection with locomotive or stationary boilers, to indicate the height of the water in the boiler.

15 An object of this invention is the provision of a water gage, in which the height of the water therein may be seen from either side of the gage, whereby the engineer or fireman of the locomotive may readily tell 40 the height of the water in the boiler from either side of the cab.

5 A further object of this invention is the provision of a water gage, the body portion of which is open on both sides, and the open 45 sides of the body being covered by glass, whereby a clear view of the water within the gage may be obtained by looking directly through the gage.

With these and other objects in view, my 30 invention consists in the novel construction, combination, and arrangement of parts, to be hereinafter more fully described, claimed, and illustrated in the accompanying drawings, in which—

25 Figure 1 is an elevational view of my improved water gage; Fig. 2 is a sectional view on the line 2—2 of Fig. 1; Fig. 3 is a longitudinal sectional view of the device; Fig. 4 is a sectional view on the line 4—4 of Fig. 40 3; Fig. 5 is a perspective view of one of the 45 clamping plates; Fig. 6 is a perspective view of one of the gaskets; and Fig. 7 is a perspective view of the body portion of the gage.

45 Referring more particularly to the drawings, the numeral 1 designates the rectangular body portion of the gage which is formed with a central longitudinal chamber 2, open at both sides of the body. The upper and lower walls of the body are provided with threaded openings 3 to receive one end of the water pipes 4, the other ends of which are connected with the boiler in the ordinary manner, whereby the height of 50 the water in the boiler will be shown by the height of the water in the chamber. Formed

in the side faces of the body are recesses 5 which communicate with the chamber 2, to provide seats for the gaskets 6 against which plates of glass 7 are adapted to rest to close 40 the open sides of the chamber. Arranged against the outer face of the glass plates 7 are gaskets 8 against which clamping members 9 are disposed to secure the glasses in their position to close the open sides of the 45 chamber. Each of the clamping members 9 comprises a rectangular plate which is provided with a central longitudinal slot 10 therein, the slot being of a width the same as the width of the chamber 2 in the body, 50 whereby when the clamping plates are secured in position, it will be seen that a person may look directly through the gage. Each of the clamping plates is provided with inwardly directed side flanges 11 and 55 end flanges 12 which are adapted to engage against the side faces of the body at its edges, the side flanges 11 being provided with offset wings 13 at their extremities to engage the side edges of the body to prevent 60 lateral movement of the clamping plates with relation to the body. Formed in the body on opposite sides of the chamber are transversely extending openings 14, and formed in the clamping plates on opposite sides of the walls 10 are similar openings 15 which are in transverse alinement with the openings 14, the alined openings being adapted to receive therethrough 65 clamping bolts 16 by means of which the 70 clamping plates may be securely clamped to the body to hold the glass plates 7 against the open sides of the body to provide tight 75 joints between the body and the glass plates. Extending inwardly from the side and end 80 flanges of the clamping plates are lugs 17 which engage the side and end edges of the 85 glass plates 7 and the outer gaskets 8, to hold the glass plates and the outer gaskets 90 in their positions to close the open sides of 95 the body. The recesses 5 in the body provide seats to receive the inner gaskets 6, whereby the same are prevented from slipping on the body and the lugs 17 on the clamping plates, when the same are connected to the body, extend inwardly so that their extremities terminate flush with the outer walls of the recesses 5 whereby the 100 glass plates and the gaskets 6 and 8 are held in such position that the edges thereof are 105 flush with each other.

From the above description taken in con-

nection with the accompanying drawing, it will be seen that I have provided a water gage, in which the parts thereof may be quickly connected together or detached from each other, so that should one of the glass plates become broken, the same may be readily removed and a new one replaced therefor.

By constructing a gage in accordance 10 with my invention, it will be understood that the height of the water in the boiler may be seen by looking at the gage from either side thereof, and as the person looking at the gage may see directly through 15 the same by reason of the glass plates closing the open sides of the body, a clearer view of the water therein is obtained than otherwise possible, as were the gage open on one side only as in the usual construction 20 of gages.

Having thus fully described my invention, what I desire to claim and secure by Letters Patent is:—

A water gage comprising a body member 25 formed with a longitudinal chamber therein, open at both sides, shoulders formed within the body and extending entirely around the openings at both sides of the body, gaskets arranged upon said shoulders so that the 30 outer faces of the gaskets will be disposed flush with the side faces of the body, glass plates arranged against the gaskets to close

the open sides of the chamber, gaskets disposed upon the outer faces of said glass plates, clamping plates arranged against the 35 second set of gaskets and having longitudinal slots formed therein in alinement with said chamber, bolts extending through the clamping plates and through the body whereby to rigidly secure the clamping plates to the 40 body, said body having openings formed in each end thereof and communicating with the chamber whereby to provide therein communication through the chamber, said clamping plates having side and end flanges 45 for engagement against the side faces of the body member to inclose said glass plates, said side flanges being provided with offset wings at their extremities to engage the side edges of the body and prevent lateral movement 50 of the clamping plates with relation to the body, and inwardly extending lugs formed on the side and end flanges of said clamping plates for engagement with the edges of said 55 glass plates, whereby to hold the same in their relative positions to close the open sides of the body.

In testimony whereof I hereunto affix my signature in the presence of two witnesses.

WILLIAM RILEY.
